UNITED STATES PATENT OFFICE.

PETER E. SINNETT, OF BUFFALO, NEW YORK.

ROOFING ELEMENT.

Application filed October 12, 1925. Serial No. 61,953.

To all whom it may concern:

Be it known that I, PETER E. SINNETT, a citizen of the United States, residing at Buffalo, in the county of Erie and State of New York, have invented new and useful Improvements in Roofing Elements, of which the following is a specification.

This invention relates to improvements in roofing elements such as shingles, tiles and the like.

In roofing composed of the ordinary well known wooden shingles which taper longitudinally, or from end to end and are lapped one upon another so that the butt ends of the shingles in one row extend over the upper ends of the shingles in the second row below, there is always left a space extending from the edge of said upper ends to where the intermediate row of shingles contacts with the roof boards. Consequentially this space is only covered with two thicknesses of shingles, and when work is being done on such a roof, it often happens that the thin parts of the intermediate shingles which overlie this space and are unsupported, become broken when stepped on, and are also liable to be weakened or warped due to snow loads in winter. Furthermore, these spaces leave openings at the sides of the roof into which wind and water can enter, thus causing rotting of the shingles, and sometimes, leakage into the building. Furthermore such roofing cannot be accurately and evenly laid without the provision of guide lines on the roof. Certain types of slate roofing are also open to the above objections.

One object of the present invention is to provide improved roofing composed of shingles or the like elements, said elements being formed with faces which are adapted to lie flat on, or contact with the roof throughout its entire area, thereby eliminating spaces between the roofing and the roof boards; and also to provide roofing elements from which a strong, weather-tight roof may be produced and which is superior to roofs constructed from the ordinary roofing elements.

Other objects are to provide a shingle or the like roofing element, from which a roof having the appearance of an expensive tiled roof may be produced; also to provide such elements with spacer or filler members or parts adapted to extend between adjacent spaced shingles, whereby said tiled effect

before mentioned may be produced and the spaces between said adjacent shingles are filled up to prevent the entrance of the weather; also to construct an element of this sort having a roof engaging face adapted to lie flat on a roof and a separate face adapted to overlie the top faces of shingles in another row; also to provide such an element which is adapted to be manufactured either from wood or from various plastic compositions as desired; also to provide shingles or the like roofing elements which are so constructed that they may be expeditiously secured on a roof in even, straight rows without the necessity of marking guide lines or other preparatory work and having means for spacing the elements both laterally and lengthwise, thus reducing the cost of laying the roof; and also to improve shingles or the like roofing elements and simplify and reduce the cost of laying such elements in the other respects herein-after specified and claimed.

In the accompanying drawings,

Fig. 1 is a plan view, partly broken away, of a portion of a roof constructed from and embodying the improved roofing element of this invention.

Fig. 2 is a side elevation of a portion of a side edge of the roof.

Fig. 3 is a face view of the under side of the improved roofing element.

Fig. 4 is a side edge view thereof.

Fig. 5 is a bottom face view of a group of the roofing elements assembled.

Figs. 6 and 7 are longitudinal cross sections of the roof on lines 6-6 and 7-7 respectively, Fig. 1.

Fig. 8 is a transverse section thereof on line 8-8, Fig. 1.

The shingle or roofing element 10 of the present invention is of preferably rectangular outline having top and bottom parallel edges 11 and 12 respectively and opposite parallel side edges 13. The upper face 14 of the shingle is a continuous flat surface, while the underside or face thereof is divided transversely into two separate, flat surfaces or areas 15 and 16 by an abrupt shoulder 17. The faces 15 and 16 are, therefore, disposed in different planes, the face 15 being disposed in angular relation to the top face 14 so as to form a wedge portion 18, which increases in thickness downwardly away from the top edge 11, while the face 16 is substantially parallel with said face

14 and forms a relatively thin butt portion 19. The butt portion 19 is preferably slightly longer than the wedge portion 18, for a reason to be described.

5 When a roof is to be laid, a number of butts or short shingles 20, of the usual wedge section, are provided for forming the first row or course overlying the eaves of the roof. These butts 20 are preferably of substantially the same length as the butt portions 19 of the shingles 10. After a row of butts have been secured in place at the eaves of the roof A, a row of the shingles 10 is positioned on the roof with the butt portions 19 thereof superimposed upon the butts 20, and the wedge portions 18 extending upwardly and with the shoulders 17 abutting against the upper edges 21 of said butts 20. The depth of the shoulders 17 is substantially equal to the thickness of the edges 21 of the butts and also of the edges 11 of the shingles 10. Consequently, by arranging one row of shingles after another upwardly over the roof surface with the shoulders 17 of one row of shingles abutting against the upper edges 11 of the row next below and with the butt portions 19 overlying the wedge portions 18 of said row, all of the lower faces 15 of the shingles will rest flatly 25 on the roof, and these faces will form a continuous contacting surface therewith. Therefore there will be no unsupported portions of the shingles, and no gaps or spaces beneath them, so that the roof will offer a substantially uniform support to any weight 30 thereon, and the edges of the roof will be substantially solid, with no openings for the entrance of the elements.

40 The butt portions 19 are, as previously stated, somewhat longer than the wedge portions 18, so that when the shingles are assembled and secured, the lower edges 12 of one row will extend downwardly beyond the upper edges 11 of the second row below, see Fig. 6, thus providing the required protection for these edges 11.

45 The shingles or roofing elements 10 are preferably all made of the same width as shown, with the exception of the narrow shingles 22, which are necessary for use at the sides of the roof to fill out the spaces in alternate rows, due to the staggered arrangement of the elements.

50 In order to produce the tiled effect shown in Fig. 1, the shingles 10 are, in accordance with the invention, provided with means for effecting a predetermined spacing of the shingles. These means shown comprise a spacing member or filler strip 25 preferably 55 formed on or secured to the under side or face of the butt portion 19 of each shingle, and which is preferably arranged midway between and parallel with the side edges 13, and has parallel side edges extending from 60 the shoulder 17 to the lower edge 12. This

filler or spacer 25 is preferably of rectangular cross section and the lower face 26 thereof, for distance beyond the shoulder 17 is in effect an extension of the face 15 of the wedge portion 18, while the remaining portion 27 of the lower face of the spacer extends in angular relation to the portion 26 and is parallel with the face 16 of the butt portion 19. When, therefore, a roof is to be prepared the butts 20 are first laid on 70 as shown, with their side edges in spaced relation such that the fillers 25 of the first row of shingles 10 will enter or engage between them, and the shoulders 17 engaging the upper edges of the butts, as explained. The remaining shingles 10 can now be laid in equal spaced relation to effect the tiled appearance, by using the spacers 25 and top edges 11 as guides for the sides 13 and shoulders 17 respectively, of adjacent shingles. 75 By forming the filler 25 with the angularly disposed face 27, the top edge portion of the shingle in the second row below is permitted to pass beneath said filler, see Fig. 7.

80 Owing to the fact that the butt portions 19 and fillers 25 are longer than the wedge portions 18 of the shingles, the space between the side portions of adjacent shingles, near the top edges 11, is closed by the fillers 25, see Figs. 1 and 8, thereby effectually preventing the entrance of the weather at these points.

85 A roof formed from the roofing elements described is very strong, is weather-proof and produces a roof of attractive appearance, such as has only been possible heretofore with relatively much more expensive roofing.

90 While the shingles or elements 10 are preferably formed with the spacers 25, these 105 spacers could be omitted, if desired, and the shingles produced with only the shoulders 17, whereby a roofing having substantially continuous contact with the roof boards 110 would be produced, and in which case shingles of different widths could be used. Separate spacer members could be provided so that this feature could be embodied in a roof, or not, as desired.

95 It is to be understood that the elements 10 115 described herein may be made either of wood, or may be molded or otherwise formed of any suitable plastic material, as desired.

100 I claim as my invention:—

105 1. Roofing which comprises a plurality of roofing elements which are adapted to be assembled in rows with the separate elements in each row in spaced relation, and with the elements in alternate rows disposed in staggered arrangement and engaging the elements of adjacent rows, and said 115 elements having portions of their lower faces which together form a substantially continuous surface which is adapted to con-

tact throughout its entire area with a roof.

2. A shingle having a straight top edge, a shoulder formed on its lower face substantially parallel with said top edge and at a distance therefrom, whereby a plurality of said shingles may be assembled in straight rows by engaging the shoulders of the shingles in one row with the top edges of the shingles of another row, and said shoulders separating the lower side of each of said shingles into two faces, one of which is adapted to rest flat on a roof, and the other of which overlies the upper face of a shingle in an adjacent row.
3. Roofing comprising a plurality of shingles of substantially rectangular outline adapted to be arranged in rows each of said shingles having a roof engaging face and other faces separated therefrom by an offset shoulder, the second faces of the shingles in one row being adapted to overlie portions of the shingles in the row next below, and a filler member extending from said shoulder upon said overlying face of each shingle and which is adapted to extend into and fill the space between the side edges of adjacent underlying shingles, and said shoulders of the shingles in one row being adapted to abut against the ends of the shingles in another row to enable the rows of shingles to be aligned one with another.
4. Roofing comprising a plurality of shingles adapted to be arranged in rows, each of said shingles having a roof engaging face and another face separated therefrom by an offset shoulder so as to extend in a relatively different plane to said roof engaging face, the second faces of the shingles in one row being adapted to overlie portions of the shingles in the row next below, and a filler member extending from
5. said shoulder upon said overlying face of each shingle and separating the same into two spaced areas and which is adapted to extend into and fill the space between adjacent underlying shingles, said overlying faces of said shingles and said filler members being of greater length than said roof engaging faces and the filler members, whereby said overlying faces of one row of shingles are adapted to extend over portions of the shingles in the second row below.
5. Roofing comprising a plurality of shingles of substantially rectangular outline adapted to be arranged in rows, each of said shingles having a roof engaging face and other faces separated therefrom by an offset shoulder, said second faces of the shingles in one row being adapted to overlie portions of the shingles in the row next below, and a filler member extending from said shoulder upon said overlying face of each shingle, and which is adapted to extend into and fill the space between adjacent underlying shingles, said filler members being cut away on their under sides to permit the edges of underlying shingles to extend beneath the same.
6. Roofing comprising a plurality of shingles, filler members on said shingles adapted to permit said shingles to be spaced in rows laterally from each other with said filler members entering the spaces therebetween, and shoulders on said shingles adapting said shingles to be spaced in lengthwise relation to each other, said shoulders being adapted to form faces, one of which is adapted to engage a roof, and said filler members each having a face which, together with said roof engaging faces, form a continuous roof engaging surface.

PETER E. SINNETT.
